UNITED STATES PATENT OFFICE.

GEORGE W. FREEMAN, OF FRANKFORT, INDIANA.

HARNESS BOX-LOOP.

SPECIFICATION forming part of Letters Patent No. 355,310, dated January 4, 1887.

Application filed August 20, 1886. Serial No. 211,389. (No model.)

To all whom it may concern:

Be it known that I, GEORGE W. FREEMAN, a citizen of the United States, residing at Frankfort, in the county of Clinton and State 5 of Indiana, have invented certain new and useful Improvements in Harness Box-Loops; and I do hereby declare that the following is a full, clear, and exact description of the same, reference being had to the annexed drawings, 10 making a part of this specification, and to the letters and figures of reference marked thereon.

Figure 1 of the drawings is a side elevation of my invention, partly in section; Fig. 2, a transverse section taken on line *y y* of Fig. 1, 15 and Fig. 3 a detail view in perspective of the box-loop.

The present invention has relation to that class of metal box-loops for blinders or other portions of harness having inwardly-bent 20 flanges for connecting it to the leather; and the invention consists in constructing these flanges so that they will be on different horizontal planes, whereby the loop can be more effectually and securely fastened to the leather 25 and held in position without the aid of stitching or riveting, as will be hereinafter described and claimed.

In the present instance I have shown my invention as used with a blinder-bridle, in order 30 to clearly illustrate its application to harness, the loop constituting my invention being shown at *A*, and what is usually termed a "box-loop." This loop *A* is of rectangular shape, and is formed upon its inner side with 35 inwardly-bent flanges *a*, a space, *b*, being left between the flanges, as shown in Fig. 3. As will be seen by reference to Fig. 2, the flanges *a* are on different planes, one of said flanges being located above the leather from which

the blinder *B* is formed, and the opposite flange 40 extending under said leather, thereby more firmly securing the loop in place and preventing it from slipping out of position. This loop, which is made out of sheet metal, can be put on after the blinder is stitched to the check-strap 45 *C*, said strap having the usual buckles, *D E*, no stitching or riveting being necessary to secure the box-loop in place, the flanges thereof holding it in position, thereby adding to the neatness and appearance of the harness, and 50 making a perfect and durable connection between it and the loop.

It should be understood that metal box-loops cannot successfully be put on a bridle-check with a machine, and all bridles made by 55 machinery require the box-loop to be connected by hand; but with a loop constructed in accordance with my invention the check-strap can be stitched to the blinder and the loop afterward slipped on and into position, thereby 60 materially reducing the cost of manufacture.

As previously stated, this box-loop is applicable to all classes of harness, and may be used on bridles with or without blinders.

Having now fully described my invention, 65 what I claim as new, and desire to secure by Letters Patent, is—

A metal box-loop for harness having inwardly-extending flanges which are on different planes, substantially as and for the purpose specified. 70

In testimony that I claim the above I have hereunto subscribed my name in the presence of two witnesses.

GEORGE W. FREEMAN.
